UNITED STATES PATENT OFFICE.

WILLIAM OWEN WALLEY, OF ALTRINCHAM, NEAR MANCHESTER, COUNTY OF CHESTER, ENGLAND.

APPARATUS FOR CHECKING AND CONTROLLING RUNAWAY HORSES.

SPECIFICATION forming part of Letters Patent No. 331,350, dated December 1, 1885.

Application filed August 22, 1885. Serial No. 175,104. (No model.) Patented in England September 6, 1884, No. 12,074; in France October 7, 1884, No. 164,646; in Belgium October 13, 1884, No. 48,830; in Germany October 18, 1884, No. 44,468, and in Austria October 22, 1884, No. 39,734.

To all whom it may concern:

Be it known that I, WILLIAM OWEN WALLEY, of Altrincham, near Manchester, in the county of Chester, England, have invented 5 certain new and useful Improvements in Apparatus for Instantly Checking and Controlling Runaway and Vicious Horses without Injury, of which the following is a specification.

10 It consists of an arrangement of straps, cords, pulleys, and rings, by means of which the driver or rider can instantly cause a powerful compression upon the windpipe of the horse, thus checking his breath and compelling him 15 to stop, and after maintaining the pressure as long as desired as instantly relieve it. It is constructed in the following manner: I take two short lengths of banding of either leather, webbing, or other suitable material. To each 20 end of each piece I attach a strong metal ring or a small pulley. One of these pieces of banding I place across the top of the horse's neck, and one beneath it round the windpipe, and connect the two rings (or blocks) on one 25 side of the neck together by a piece of silk (or other) cord or by a narrow leather strap, one end of which I attach permanently to the lower ring (or block) on one side, and then pass it through the upper ring or block on the 30 same side, then through the lower ring, (or block,) and finally again through the upper ring, (or block,) when I carry it over to the other side of the horse's neck, and repeat the process with the other end through the other 35 two rings, (or blocks.)

The apparatus now forms a collar round the neck of the horse, and upon pulling the cord where it crosses the horse's neck a powerful pressure is immediately brought to bear upon 40 the windpipe of the horse. I now attach to the lower ring on each side an elastic band or spiral spring, which I connect by means of a suitable fastening with the ring of the bit. This arrangement slackens the tightening cord 45 (or strap) directly the user relieves his strain upon it.

The above arrangement is suitable for draft-horses. For riding, I attach the ends of the cord or strap to the upper rings, and pull it through the lower rings, thus placing it in a 50 position where it can be held like a curb-rein by the rider.

I have so far described for illustration the manner in which the apparatus is made; but in practice the whole apparatus is kept ready 55 for use with the cord (or strap) rove through the rings or pulleys, and can be placed round the horse's neck, and buckled by means of a buckle in the lower piece of banding, and when the ends of the elastic bands (or spiral springs) 60 are hitched to the bit-ring is instantly ready for use.

By means of this apparatus a vicious horse can be ridden or driven without a bit.

In order that the foregoing may be better 65 understood, I attach hereunto a sheet of drawings, in which—

Figure 1 shows the apparatus as arranged for riding, and Fig. 2 as arranged for driving.

In both figures the letter *a a* indicates the two short pieces of banding; *b b*, the two rings, (which may be exchanged for any sort of suitable pulley or sheave blocks;) *c c*, the silk cord (or thin strap,) and *e e* the elastic bands (or 75 spiral springs) connecting the apparatus with the bit-ring.

Having thus described my invention, I desire to claim—

A checking apparatus consisting of the 80 bands *a a* with rings *b b*, the elastic bands *e e*, attached to the bridle and rings *b*, and the cords *c c*, all arranged, combined, and operated substantially as and for the purpose set forth.

In testimony that I claim the foregoing I have hereunto set my hand this 10th day of August, 1885.

WILLIAM OWEN WALLEY.
